DESIGN FOR A SINK

Alfred H. Haberstump, Detroit, Mich., assignor
to The Murray Corporation of America, De-
troit, Mich., a corporation of Delaware

Application September 27, 1939, Serial No. 87,392

Term of patent 14 years

To all whom it may concern:

Be it known that I, Alfred H. Haberstump, a citizen of the United States of America, residing in Detroit, in the county of Wayne, State of Michigan, have invented a new, original, and ornamental Design for a Sink, of which the following is a specification, reference being had to the accompanying drawing, forming a part thereof, wherein:

Figure 1 is a perspective view of a sink embodying my new design, with a portion shown in dotted lines;

Fig. 2 is a plan view of the sink illustrated in Fig. 1; and,

Fig. 3 is a sectional view of the sink illustrated in Fig. 2 taken on the line 3—3 thereof.

The essential features of the design reside in the portion shown in full lines.

I claim:

The ornamental design for a sink, substantially as shown and described.

ALFRED H. HABERSTUMP.
